EBERHARD FABER, OF NEW YORK, N. Y.

Design No. 3,219, dated November 3, 1868.

DESIGN FOR A PENCIL TRADE-MARK

The Schedule referred to in these Letters Patent and making part of the same.

To all whom it may concern:

Be it known that I, EBERHARD FABER, of the city, county, and State of New York, have invented a new and original Design for Trade-Mark on Pencils; and I do hereby declare the following to be a full, clear, and exact description thereof, which will enable those skilled in the art to make and use the same, reference being had to the accompanying drawing, forming part of this specification.

The drawing represents an elevation of this invention.

My design consists of a bouquet or bunch of flowers, A, applied to a pencil, so that a novel and elegant

appearance is imparted to such pencil, whereby the same can be readily distinguished from pencils of other manufacturers.

Having thus described my invention,

What I claim as new, and desire to secure by Letters Patent, is—

The design for a trade-mark on pencils, as herein shown and described.

EBERHARD FABER.
